SELF-DRAPE CURTAIN

Henry Chester Baxter, Babylon, N. Y., assignor
to Andrew McLean Company, New York, N. Y.,
a corporation of New Jersey

Application June 14, 1933. Serial No. 675,860

17 Claims. (Cl. 156—10)

This invention is a window curtain which, by virtue of its special construction, automatically gives a draped-back effect when hung in the usual way, yet without the necessity of using the tie-back which is commonly used with a curtain for giving such draped effect.

An important feature of the invention is that the lower edge of the curtain is substantially horizontal, thereby presenting a distinctly improved appearance over the ordinary draped curtain, where the lower edge extends upwardly and has a pulled-up effect. This feature is, however, optional.

According to this invention, the curtain, which is approximately the length of the window, is, at a point intermediate its upper and lower edges, gathered or narrowed, and is preferably held in that gathered position by some ornamental device which simulates the usual tie-back. This ornamental device preferably extends diagonally upwardly and outwardly from the inner edge of the curtain. The curtain, when hung, automatically presents a draped effect, and preferably has its lower edge substantially horizontal.

While the curtain may be made from a single piece of material, the preferred embodiment of the invention is a curtain made from two pieces of material.

In the preferred embodiment, the curtain, which, in its entirety, is approximately the length of the window and about half the width of the window, is made in two parts, about equal in vertical extent, although the relative proportions of the two parts can be varied at will. The two meeting or joining edges of the curtain are preferably cut on the bias and joined together along their bias edges. Usually the upper part will be longer than the lower part, because the tie-back is nearer the bottom of the curtain. The lower edge of the upper part, and the upper edge of the lower part, are gathered together and secured substantially permanently to each other along a line which is substantially narrower than the normal width of the curtain. The line of meeting of these two parts of the curtain may be approximately at the middle of the window or perhaps somewhat lower, being positioned at the place where the tie-back, commonly used for giving a draped effect, is placed.

The line of meeting of the two curtain parts could extend substantially horizontally, but in the preferred embodiment of the invention, the line of meeting of the two parts extends diagonally upwardly, away from the center of the window, at about the angle that is normally assumed by

the ordinary tie-back, that is to say, about 30°.

In the preferred embodiment of the invention the lower edge of the upper part of the curtain, and the upper edge of the lower part, are cut on the bias and secured together by a strip of material which extends all the way around the curtain, the meeting edges of the two curtain portions being gathered and held in gathered relationship along a diagonal line which extends upwardly and outwardly away from the center of the window. This strip of material may, if desired, be of a color contrasting with the material of the curtain; this strip gives the effect of a tie-back as commonly used.

The lower edge of the curtain, in the several embodiments, is preferably made to extend horizontally.

As a result of this construction, the curtain, when hung in the usual way, immediately and automatically assumes a draped back effect without the necessity of using the tie-back, and consequently there is no need to mar the side portions of the window with screw eyes or hooks to which the ordinary tie-back is commonly attached.

Where the curtain is made in two parts, it may be made in two colors which, although contrasting, are made to harmonize with each other and with the furnishings of the room. Furthermore, the upper parts of the curtains are usually more or less visible from the street, while the lower parts of the curtain, those below the transversely extending strip above mentioned, are not readily visible from the street, being more or less screened by the side of the window. For this reason, the upper parts of all the curtains in the house may be made of the same color, thereby giving the effect as seen from the outside, of a uniform use of color in all the curtains throughout the house; the lower portions of the same curtains in the different rooms could be made of different colors so as to harmonize with the furnishings of that particular room.

The more specific features of the invention having been thus outlined, reference will now be made to the accompanying drawing, illustrating in more detail the present preferred embodiment of the invention.

In the drawing:

Fig. 1 is a view of the two parts from which the curtain is made;

Fig. 2 shows the two parts of the curtain with adjoining edges gathered;

Fig. 3 shows the completed curtain.

Referring now to the drawing wherein similar reference characters indicate similar parts:

Fig. 3 shows the completed curtain for half the window, a similar half being used, of course, for the other side of the window. This curtain comprises an upper portion 2, the upper edge of which 5 may be provided with known means for attachment to a curtain rod or the like and which also, for decorative purposes, may be gathered as shown at 4, and provided with a decorative strip as at 6. The lower edge 7 of the upper part 2 10 of the curtain, and the upper edge 8 of the lower part 9 of the curtain, are cut on the bias along a line indicated generally at 10, which line extends diagonally upwardly and outwardly away from the center of the window. The angle of the line 15 10 is preferably between 20° and 50°. These diagonal edges are gathered together as shown in Fig. 2, by stitches or the like 11 so as to be substantially narrower than the normal width of the curtain and are secured to each other in the 20 gathered position, along the diagonally extending line 10 by a strip of material 12, which preferably encircles the curtain and is secured to the upper and lower portions thereof by stitches or the like. This strip 12 may be made of any suitable color and may be as decorative as necessary. When the curtain is hung it immediately and 25 automatically assumes a draped-back position and looks like a draped-back curtain, although there is no tie-back whatever used and consequently no screw eyes, hooks or brackets are necessary, thereby eliminating any possible marring of the woodwork by the insertion of such hooks or brackets. The lower edge 9a of the curtain preferably extends substantially horizontally. 30

Where the curtain is made in a single piece, the curtain is gathered together at a point between top and bottom and held in the gathered position by any suitable means, such as stitches and an ornamental strip or device like the strip 35 14.

The two parts of the curtain may be made of the same or contrasting colors, and of the same or different materials. Since the upper parts of the several curtains are visible from the street 45 when the shades are up, the upper parts of all the curtains in the house may be made of the same color, thereby giving a matched effect, while the lower parts of the several curtains, which are more or less hidden by the window 50 frame, may be made of different colors in different rooms of the house so as to harmonize with the furnishings in the room where the curtain is hung. While the gathered meeting edges of the two curtain portions meet on a diagonal it would 55 be possible to have them meet nearly along a horizontal line and still get a draped effect, although in the preferred embodiment of the invention, the meeting line extends diagonally upwardly and outwardly away from the center of the window. 60

While the preferred embodiments of the invention have been described, it should be understood that the invention is not limited to the precise details described, but that it may be carried out in other ways, as falling within the scope of the appended claims. 65

I claim as my invention:

1. A self-draping window curtain which, at a point intermediate the top and bottom of the curtain, is gathered so as to be substantially narrower than the normal width of the curtain, and means 70 for holding the curtain in gathered position substantially permanently, whereby the curtain automatically assumes a draped-back effect when hung. 75

2. A self-draping window curtain which, at a point intermediate the top and bottom of the curtain, is gathered so as to be substantially narrower than the normal width of the curtain, and means for holding the curtain in gathered position 80 substantially permanently, whereby the curtain automatically assumes a draped-back effect when hung, the lower edge of the curtain being substantially horizontal.

3. A self-draping window curtain which, at a point intermediate the top and bottom of the curtain, is gathered so as to be substantially narrower than the normal width of the curtain, and means, engageable with the gathered part of the curtain and extending diagonally upwardly, away from 90 the middle of the window, for holding the curtain in gathered position substantially permanently, whereby the curtain automatically assumes a draped effect when hung. 95

4. A self-draping window curtain which, at a point intermediate the top and bottom of the curtain, is gathered so as to be substantially narrower than the normal width of the curtain, and means, engageable with the gathered part of the curtain and extending diagonally upwardly, away from 100 the middle of the window, for holding the curtain in gathered position substantially permanently, whereby the curtain automatically assumes a draped effect when hung, the lower edge of the curtain being substantially horizontal. 105

5. A self-draping window curtain which, at a point intermediate the top and bottom of the curtain, is gathered so as to be substantially narrower than the normal width of the curtain, and means comprising a strip of material, secured to the gathered part of the curtain, for holding the curtain in gathered position substantially permanently, whereby the curtain automatically assumes a draped-back effect. 110

6. A self-draping window curtain which, at a point intermediate the top and bottom of the curtain, is gathered so as to be substantially narrower than the normal width of the curtain, and means comprising a strip of material, secured to the gathered part of the curtain, for holding the curtain in gathered position substantially permanently, 120 said strip of material extending diagonally upwardly and outwardly, across the curtain. 125

7. A self-draping window curtain which, at a point intermediate the top and bottom of the curtain, is gathered so as to be substantially narrower than the normal width of the curtain, and means comprising a strip of material, secured to the gathered part of the curtain, for holding the curtain in gathered position substantially permanently, 130 said strip of material extending diagonally upwardly and outwardly, across the curtain, the lower edge of the curtain being substantially horizontal. 135

8. A self-draping window curtain, comprising in combination an upper portion and a lower portion, the lower edge of the upper portion and the upper edge of the lower portion being secured together along a line which is substantially shorter than the normal width of the curtain, the joining edges of both portions of the curtain being gathered along their meeting line, thereby giving a draped-back effect to the curtain when hung. 140

9. A self-draping window curtain, comprising in combination an upper portion and a lower portion, the lower edge of the upper portion and the upper edge of the lower portion being cut on the bias, and gathered, and joined together along such cut edges, the joining line being substantially 145 150

shorter than the normal width of the curtain, thereby giving a draped-back effect to the curtain when hung.

10. A self-draping window curtain, comprising in combination an upper portion and a lower portion, the lower edge of the upper portion and the upper edge of the lower portion being cut on the bias, and gathered, and joined together along such cut edges, the joining line being substantially shorter than the normal width of the curtain, thereby giving a draped-back effect to the curtain when hung, the lower edge of the curtain being substantially horizontal.

11. A self-draping window curtain, comprising in combination an upper portion and a lower portion, the lower edge of the upper portion and the upper edge of the lower portion being cut on the bias, and gathered, and joined together along such cut edges, the joining line being substantially shorter than the normal width of the curtain, and extending diagonally upwardly, away from the center of the window, thereby giving a draped-back effect to the curtain when hung in the usual way.

25 12. A self-draping window curtain, comprising in combination an upper portion and a lower portion, the lower edge of the upper portion and the upper edge of the lower portion being cut on the bias, and gathered, and joined together along such cut edges, the joining line being substantially shorter than the normal width of the curtain, and extending diagonally upwardly, away from the center of the window, thereby giving a draped-back effect to the curtain when hung in the usual way, the lower edge of the curtain being substantially horizontal.

13. A self-draping window curtain, comprising in combination an upper portion and a lower portion made of different colored materials, the lower edge of the upper portion and the upper edge of the lower portion being secured together along a line which is substantially shorter than the normal width of the curtain, the joining edges of both portions of the curtain being gathered along their meeting line, thereby giving a draped-back effect to the curtain when hung.

40 14. A self-draping window curtain, comprising in combination an upper portion and a lower portion, the lower edge of the upper portion and the upper edge of the lower portion being

secured together along a line which is substantially shorter than the normal width of the curtain, the joining edges of both portions of the curtain being gathered along their meeting line, and a strip of material overlapping the meeting edges of the two portions of the curtain and secured thereto, for holding such edges in the gathered state.

45 15. A self-draping window curtain, comprising in combination an upper portion and a lower portion, the lower edge of the upper portion and the upper edge of the lower portion being secured together along a line which is substantially shorter than the normal width of the curtain, the joining edges of both portions of the curtain being gathered along their meeting line, and a strip of material, extending entirely around the curtain and overlapping the meeting edges of the two portions of the curtain and secured thereto, for holding such edges in the gathered state.

50 16. A self-draping window curtain, comprising in combination an upper portion and a lower portion, the lower edge of the upper portion and the upper edge of the lower portion being cut on the bias, and gathered, and joined together along such cut edges, the joining line being substantially shorter than the normal width of the curtain, and a diagonally extending strip of material overlapping the meeting edges of the two portions of the curtain and secured thereto, for holding such edges in the gathered state, the curtain, when hung, having a draped-back effect without the necessity of using a separate tie-back.

55 17. A self-draping window curtain, comprising in combination an upper portion and a lower portion, the lower edge of the upper portion and the upper edge of the lower portion being cut on the bias, and gathered, and joined together along such cut edges, the joining line being substantially shorter than the normal width of the curtain, and a diagonally extending strip of material encircling the curtain and overlapping the meeting edges of the two portions of the curtain and secured thereto, for holding such edges in the gathered state, the curtain, when hung, having a draped-back effect without the necessity of using a separate tie-back.
